ROAD JOINT END SEAL

Robert R. Robertson, Chicago, Ill., assignor to The
Translode Joint Company, Chicago Heights,
Ill., a corporation of Illinois

Application June 10, 1937, Serial No. 147,500

13 Claims. (Cl. 94—18)

The present invention pertains to road joints, and more particularly to improved end seals for closing the outer ends of the joints adjacent the road shoulder. During the construction of the road, the improved joint end seals are disposed against the outer ends of the joints and are contacted by the road side forms. The improved end seal is provided with means for anchoring the same to the joint and in the concrete road slabs on opposite sides of the joint. The end seal is provided with an inherently expandable sealing pad of sponge rubber or similar material which is so positioned that the same is adapted to be pre-compressed during the assembly of the end seal to provide a tight sealing contact with the end of the road joint before as well as after the concrete has been poured and after the road side form has been removed.

It is an object of this invention to provide a transverse road joint with an improved and simplified form of end seal positioned across the outer end of the joint and having means whereby the end seal may be successively anchored to the road joint and then to the concrete slabs between which the road joint is embedded.

Another object of the invention is the provision of a road joint end seal including a compressible and inherently expandable sealing pad having adjustable means associated therewith for compressing the pad and holding the same in position with the assistance of side retainers for holding projecting side margins of the pad anchored in the concrete in which the road joint is embedded.

It is furthermore an object of this invention to provide a road joint end seal including an inherently expandable sealing pad constructed of compressible material, the side margins of which are provided with wire anchors for embedding in the concrete forming the slabs on adjacent sides of the road joint.

It is an important object of this invention to provide an improved and simplified form of road joint end seal including a pre-compressed sealing pad having a plate member associated therewith, with said plate member having anchoring bolts for adjustable engagement with side members rigidly secured to the sides of the road joint affording a tight adjustable seal at the end of the joint, and with the concrete slabs on adjacent sides of the joint by the use of side anchoring units portions of which are adapted to be embedded in the concrete road slabs.

Other and further important objects of this invention will be apparent from the disclosures

in the specification and the accompanying drawings.

The invention (in a preferred form) is illustrated in the drawings and hereinafter more fully described.

On the drawings:

Figure 1 is a fragmentary side elevational view of a road joint, having a road end seal embodying the principles of this invention engaged against the outer end of the joint to the inside of a road side form which is illustrated in section.

Figure 2 is a transverse vertical sectional view taken on the line II—II of Figure 1.

Figure 3 is a fragmentary top plan view of the joint end seal disposed between the road joint and the side form.

Figure 4 is a similar fragmentary top plan view of the mechanism shown in Figure 3 after the same has been embedded in concrete.

Figure 5 is a side elevational view of a modified form of road joint end seal disposed between the outer end of a road joint and adjacent a road side form illustrated in section.

Figure 6 is a front view of the sealing and anchoring face of the sealing pad of the type illustrated in Figure 5.

Figure 7 is a side elevational view of another modified form of road joint end seal engaged between the outer end of a road joint and a road side form shown in section.

Figure 8 is a top plan view of the modified form of seal shown in Figure 7.

As shown on the drawings:

In the form of the device illustrated in Figures 1 to 4, inclusive, the reference numeral 1 indicates a road side form disposed longitudinally of the side edge of the road and crossing the outer end of a transverse road expansion joint. The expansion joint comprises an upper filler core board 2 and a lower filler or core board 3 separated by a reinforced intermediate shield portion 4. The shield portion 4 is adjustable and has connected therewith an upper shield plate 5 and a lower shield plate 6 which are positioned on diagonally opposite sides of the filler or core. Welded or otherwise rigidly secured to the outer faces of the upper and lower joint plates 5 and 6 and near the outer ends thereof are threaded blocks or nuts 7, which, as illustrated in Figure 2, are disposed on opposite sides of the joint and on diagonally opposite sides of the adjustable shield portion 4 of the joint.

The shield portion 4 includes hollow or tubular side portions, the outer ends of which open to the

side of the road and are adapted to be sealed by the improved end seal of this invention. The improved end seal is disposed between the outer end of the road joint and the road side form 1, and comprises a sealing cushion or pad 8 constructed of an inherently expansible compressible material, such as sponge rubber or the like. The sealing pad or cushion 8 is wide enough to project beyond the sides of the road joint. Seated 10 against the outer surface of the sealing pad or cushion 8 is a pressure plate 9, the upper margin of which is bent over at substantially right angles to provide a top flange 10 which seats on the top of the sealing pad 8. Each side margin of the sealing pad 8 is provided with apertures through which a pair of upper and lower wire anchoring arms 11 project. The ends of the anchoring arms 11 are deflected or bent over to provide anchoring hooks 12. The outer ends of the anchoring arms 11 are integrally connected by means of a connecting wire 13 which seats against the outer surface of the sealing pad. The anchoring arms 11 together with the connecting member 13 form a U-shaped anchoring unit whereby a side margin of the sealing pad is adapted to be anchored in one of the concrete road slabs 14 within which the road joint is embedded.

Projecting through apertures in the compression plate 9 are clamping bolts 15, the threaded 30 ends of which project through the sealing pad 8 and are threaded into the retaining nuts 7 to draw the plate 9 towards the outer end of the joint thereby compressing the sealing pad 8 to tightly clamp the same against the outer end of the joint, permitting portions of the compressible material forming the sealing pad to bulge into the ends of the hollow portions of the shield 4 of the joint. With the compression of the middle section of the sealing pad 8 against the end of the joint, the side margins of the sealing pad are inclined to bulge outwardly around the side edges of the compression plate 9.

With the end seal mechanism positioned between the road side form 1 and the outer end of the expansion joint mechanism, as illustrated in Figure 3, concrete is poured on opposite sides of the joint to form the concrete road slabs 14, with the concrete material embedding the anchoring arms 11. The side anchoring units for the joint 50 hold the side margins of the pad compressed against the concrete slabs 14, as clearly illustrated in Figure 4.

The improved sealing pad 8, when clamped in position as illustrated in Figure 4, is adapted to 55 completely seal the end of the joint at substantially all times for the reason that the pad is adapted to be compressed or expanded with the respective expansion and contraction of the road slabs 14 due to temperature changes. It will also be noted that the sealing pad 8 may be adjusted 60 through the bolts 15.

Figures 5 and 6 illustrate a modified form of road joint end seal adapted, before pouring of the concrete, to be engaged against the outer end 65 of a road joint adjacent one side of the road side form similar to the arrangement illustrated in Figure 1. The modified form of end seal is similar to that shown in Figure 1, with the exception that the sealing pad or cushion 8 is replaced by 70 a modified form of sealing pad or cushion 16 constructed of sponge rubber or other suitable material. Integrally formed on one surface of the sealing pad 16, are a plurality of rows of staggered anchoring knobs or buttons 17 which are formed 75 tapered inwardly from the outer ends toward the

pad 16, so that when concrete is poured on opposite sides of the road joint, the knobs or buttons 17 are embedded in the concrete to hold the side portions of the pad anchored in position, while the middle portion of the pad seats against the outer end of the joint to close any openings therein and to form a seal at the end of the joint. 5

Figures 7 and 8 illustrate another modified form of sealing pad or cushion adapted to be secured in position between the outer end of a road joint 10 and a road side form. The parts which are similar to those illustrated and described in connection with Figures 1 to 6, inclusive, are designated by corresponding reference numerals. The improvement lies in the sealing pad or cushion, 15 which comprises a pad 18 constructed of sponge rubber or other suitable material. The pad or cushion 18 is provided with integral dovetail anchoring ribs 19 which project outwardly from the longitudinal margins of one face of the pad 18 20 into a position to be conveniently embedded in the concrete to hold the pad anchored in position.

It will, of course, be understood that many details of construction may be varied through a wide range without departing from the principles 25 of this invention, and it is, therefore, not the purpose to limit the patent granted hereon otherwise than necessitated by the scope of the appended claims.

I claim as my invention:

1. The combination with an expansion joint embedded between concrete road slabs, of internally threaded members rigidly secured to the sides of the joint, and an end seal for the expansion joint comprising an inherently expansible 30 seal pad engaged against the outer end of the expansion joint, a plate member engaged against the seal pad, and retaining bolts projecting through the plate and through the seal pad into threaded engagement with the internally threaded 35 members on the sides of the joint for compressing the seal pad against the outer end of the joint and against the concrete slabs to form a tight seal at the end of the expansion joint.

2. The combination with an expansion joint 45 embedded between concrete road slabs, of internally threaded nut members rigidly secured to the sides of the expansion joint, a compressible inherently expansible seal pad engaged against the outer end of the expansion joint and partly 50 embedded in the road slabs, a plate member engaged against the seal pad, and bolt members projecting through the plate and through the seal pad into threaded engagement with the nut members on the sides of the expansion joint, said 55 bolt members being adjustable for compressing the seal pad against the end of the joint and against the sides of the road slabs for producing a tight seal at the end of the joint.

3. The combination with a transverse road 60 joint embedded between concrete road slabs, of a sealing unit for the road joint comprising a compressing and expansible pad, a metal shield engaging the same, threaded projections engaged on opposite sides of the road joint, and bolt members projecting through the shield and through the pad into adjustable threaded engagement with the threaded members on the road joint for regulating the pressure of the pad against the end of the joint to seal the 70 same.

4. The combination with a transverse road 75 joint embedded between concrete road slabs, of a sealing unit engageable at the outer end of the joint and comprising a compressible pad, clamp- 75

ing means adjustably connected with the road joint for varying the pressure of the pad against the end of the joint, and means for anchoring projecting portions of said pad to the concrete road slabs.

5. The combination with a transverse road joint embedded between concrete road slabs, of an end seal for the road joint comprising a compressible pad, anchoring members connected with the pad and embedded in the concrete road slabs on opposite sides of the joint, nut members projecting from opposite sides of the road joint, and bolts projecting through the pad into threaded adjustable engagement with the nut members on the road joint.

10. The combination with a transverse road joint embedded between concrete road slabs, of a compressible pad engaged against the outer end of the road joint, anchoring members connected with the pad and embedded in the concrete road slab on opposite sides of the joint, nut members projecting from opposite sides of the road joint, a cover for said pad, and bolt members projecting through the cover and through the pad into threaded adjustable engagement with the nut members for varying the pressure of the pad against the outer end of the joint to seal the same.

15. The combination with a transverse road joint embedded between concrete road slabs, of an inherently expandable and compressible sealing pad engaged against the end of the road joint and overlapping the road slabs, means adjustably connected with the road joint for varying the pressure of the pad against the end of the road joint, and anchoring means on the pad embedded in the concrete road slabs.

20. The combination with a transverse road joint embedded between concrete road slabs, of an expandable and compressible sealing pad engaged against the outer end of the joint and overlapping the road slabs, staggered anchor members in the overlapping portions of the pad embedded in the concrete road slabs for holding the sealing pad in position to seal the end of the joint.

25. The combination with a transverse road joint embedded between concrete road slabs, of

an expandable and compressible sealing pad engaged against the outer end of the road joint and overlapping the road slabs, dovetail anchoring ribs on the pad embedded in the concrete road slabs, and clamping means adjustable with respect to the road joint and connected therewith for clamping the pad against the road joint and against the road slabs to seal the end of the joint.

30. The combination with a road joint, of nut members secured to opposite sides thereof near an end of the joint, a plate member disposed transversely of the end of the joint, a sealing pad engaged between the end of the joint and the plate member, and bolts projecting through the plate member and the pad into threaded engagement with the nut members on the sides of the joint for holding the pad compressed against the end of the joint to seal the joint.

35. The combination with a road joint embedded between concrete road slabs, of a sealing pad engaged against the end of the joint and overlapping the road slabs, means for clamping the pad against the end of the joint to seal the same, and anchoring members integrally formed on the pad and embedded in the concrete slabs.

40. The combination with means defining a transverse road joint structure, of a compressing member disposed across the end of the joint, a compressible sealing medium between said member and the end of the joint, and adjustable means connecting said member and said joint structure for forcing them toward each other to increase the sealing effect of said sealing medium.

45. The combination with means defining a transverse road joint of a compressing member disposed across the end of the joint, a compressible sealing medium between said member and the end of the joint, and means adjustably connecting said member with opposed sides of the joint and arranged movable to force said member toward the end of the joint to increase the sealing effect of said sealing medium.

ROBERT R. ROBERTSON.
